United States Patent Office

Des. 192,376

Patented Mar. 13, 1962

192,376

CONDIMENT DISPENSER

Marvin Marcus, Shaker Heights, Ohio, assignor to The Superior Provision Company, Massillon, Ohio, a corporation of Ohio

Filed Aug. 8, 1961, Ser. No. 66,244

Term of patent 14 years

(Cl. D44—22)

FIG. 2 is a top plan view thereof;

FIG. 3 is a bottom plan view thereof;

FIG. 4 is a view of one side thereof;

FIG. 5 is a view of another side thereof; and

FIG. 6 is a rear view thereof.

I claim:

The ornamental design for a condiment dispenser, substantially as shown.
